His Attorney.

UNITED STATES PATENT OFFICE.

PETER ZIMBELMANN, OF AURORA, ILLINOIS.

DOOR CHECK.

1,422,163.

Specification of Letters Patent. Patented July 11, 1922.

Application filed July 19, 1920. Serial No. 397,523.

To all whom it may concern:

Be it known that I, PETER ZIMBELMANN, a citizen of the United States, and a resident of the city of Aurora, county of Kane, and 5 State of Illinois, have invented certain new and useful Improvements in Door Checks, of which the following is a specification.

My invention relates to improvements in door checks especially adapted for use in 10 conjunction with the trap doors on railway vestibules, and has for its object the provision of an improved construction of this character which is strong and durable in use and efficient in operation.

15 Other objects will appear hereinafter.

The invention consists in the combinations and arrangements of parts hereinafter described and claimed.

The invention will be best understood by 20 reference to the accompanying drawings forming a part of this specification, and in which,

Fig. 1, is a view illustrating a door check embodying the invention in position of use 25 on a vestibule trap door,

Fig. 2, a partial longitudinal section of said door check, and

Fig. 3, a section taken on line 3—3 of Fig. 1.

30 The preferred form of construction, as illustrated in the drawings, comprising a tubular housing 4 open at one end but closed at its other end by means of a head or cap 5 having a perforated lug 6 thereon 35 adapted to be pivotally secured to a bracket 7 on the under side of an ordinary railway car vestibule trap door 8 as indicated. The trap door 8 is pivoted at 9 on a bracket 10 secured to the end of the car and 40 whereby said trap door may be readily swung upwardly against said car end when it is desired to use the steps of the car.

A stem or rod 12 is arranged to operate 45 within the housing 4, said stem being threaded for a considerable distance from its inner end and a cap 13 being threaded over the inner end of said stem. The cap 13 carries a piston 14 snugly fitting within the housing 4 to frictionally resist movement between said stem and housing. A second housing 15 is slidably fitted over the open end of housing 14 and the other end 50 16 of the housing is threaded on the stem 12 as shown. The housing 15 is provided with 55 an air vent opening 17 and a sleeve 18 is imprisoned between the inner end of cap 13

and the end of housing 16 to surround the stem 12 as shown. At its outer end the stem 12 is provided with an eye 19 arranged to be pivotally connected by means of a 60 bolt 20 with the bracket 10. A removable threaded plug 21 is provided in the head 5 and by means of which a lubricant such as a heavy oil or grease may be introduced into the interior of the housing 4 and a suitable supply of lubricant is also introduced into the housing 15 before the parts are assembled. By this arrangement, it will be observed, that the movements of the trap door 8 will be adequately checked to prevent 70 sudden shocks and jars. The operating parts will also be thoroughly and constantly lubricated and protected from the entry of dust or dirt. The specific form and arrangement of parts is a simple and efficient one 75 for the purpose, and provide a door check of the class described which is strong and durable in use, and capable of economical manufacture.

While I have illustrated and described the 80 preferred form of construction for carrying my invention into effect, this is capable of variation and modification without departing from the spirit of the invention. I, therefore, do not wish to be limited to the 85 precise details of construction set forth, but desire to avail myself of such variations and modifications as come within the scope of the appended claims.

Having described my invention, what I 90 claim as new and desire to secure by Letters Patent is:—

1. A door check comprising a tubular housing; a threaded stem fitting into said housing; a piston adjustably threaded on 95 said stem and operating in said housing; and a second housing mounted for movement with said stem and slidably fitting over said first mentioned housing, substantially as described.

2. A door check comprising a tubular housing; a threaded stem fitting into said housing; means surrounding and threaded on the inner end of said stem; a piston on the inner end of said means operating in said 105 housing; and a second housing adjustably mounted on said stem in engagement with said means and slidably fitting said first mentioned housing, substantially as described.

3. A door check comprising a tubular housing; a threaded stem fitting into said

100

105

110

housing; a piston on the inner end of said stem operating in said housing; and a second housing threaded on said stem to move therewith and slidably fitting over said first mentioned housing, said second mentioned housing having an air vent opening therein, substantially as described.

4. A door check comprising a tubular housing open at one end and having a head 10 closing the other end; a perforated lug on said head for pivotally connecting the same with the under side of the trap door; a removable threaded plug extending through said head and permitting of the introduction 15 of lubricant into said housing; a threaded stem having an eye at its outer end for pivotally mounting the same, the inner end of said stem being arranged to project into said

housing; a cap threaded over the inner end of said stem; a piston carried by said cap and fitting within said housing; a second housing slidably fitting over said first mentioned housing and having its end threaded on said stem, there being an air vent in said second mentioned housing; and a sleeve 25 surrounding said stem and held in place thereon by said cap, substantially as described.

In testimony whereof I have signed my name to this specification in the presence of 30 two subscribing witnesses.

PETER ZIMBELMANN.
